UNITED STATES PATENT OFFICE.

EDMUND M. HULL, OF BUFFALO, NEW YORK.

LOADING-SPOUT.

1,358,446.

Specification of Letters Patent. Patented Nov. 9, 1920.

Application filed October 5, 1917. Serial No. 194,960.

To all whom it may concern:

Be it known that I, EDMUND M. HULL, a citizen of the United States, residing at Buffalo, in the county of Erie and State of New York, have invented a new and useful Improvement in Loading-Spouts, of which the following is a specification.

This invention relates to loading spouts or "horns" of the sort which are used at grain elevators for chuting the grain from the elevator into grain cars for loading the latter. Such spouts or "horns" are attached to the lower end of the grain chute or leg descending from the elevator, and have branches which are curved so as to project into the car through the door opening in the side thereof and also curve or diverge away from each other so that the grain discharging therefrom is directed toward the opposite ends of the car. With the spouts or "horns" as heretofore constructed, it has been impossible to completely fill the cars to the ends and up to the roof thereof without shoveling or otherwise moving the grain in the cars. The spouts have been of such form that the momentum of the discharging grain is materially decreased and is not sufficient when leaving the ends of the spouts to throw the grain to the ends of the car after the same has been partly filled, especially in the case of the long cars which are now in common use for carrying grain.

The object of this invention is to provide a spout of this nature which is of a novel form, such that it is adapted to deliver the grain from the point midway between the ends of the car where the spout is located to the ends of the car, and to completely fill the car up to its roof without necessitating any shoveling or moving of the grain subsequent to its delivery into the car by the spout.

In the accompanying drawings:

Figure 1 is a front elevation of a loading spout embodying the invention, showing in section the body of a car being loaded.

Figs. 2 and 3 are enlarged sections thereof on lines 2-2 and 3-3, respectively, Fig. 1.

Fig. 4 is a side elevation thereof, showing by broken lines the car body and support for the spout.

Fig. 5 is an enlarged fragmentary front elevation of the spout.

Fig. 6 is a sectional elevation thereof, showing by full and broken lines, different positions of the deflector.

Fig. 7 is a sectional elevation thereof on line 7-7, Fig. 5.

Fig. 8 is an enlarged section of one branch of the spout on line 8-8, Fig. 4.

A represents the lower portion of the discharge chute or leg of a grain elevator. The spout forming the subject matter of this invention is attached to the lower end of this chute or leg A.

The spout preferably comprises an upper section B which is telescopically connected with the lower end of the chute A to enable the spout to be raised or lowered as may be necessary to locate it at the required elevation, and a branched section C which is hinged to the lower end of the telescopic section B and is formed with opposite branches c c which curve forwardly and downwardly from the telescopic section so as to project into a car through the side door opening thereof, and also curve or diverge away from each other toward the ends of the car. The section B may be telescopically connected to the chute or leg A in any suitable manner. As shown, the telescopic section surrounds the lower end of the leg or chute and is connected thereto by a chain or rope 10 passing around pulleys 11 and 12 attached respectively to the fixed and telescopic sections so that the latter section can be raised or lowered and secured at the desired elevation by means of the rope or chain in a well known manner. 14 indicates guide bars for the telescopic section fixed at their upper ends to the opposite sides of the lower end of the chute A and extending through guide openings 15 in straps 16 passing around and fixed on the telescopic section.

The upper end of the branched or lower section C of the spout, like the telescopic section B, is of rectangular shape in cross-section and fits over the lower end of the telescopic section, and each of the curved branches or horns c c of this lower section is also of rectangular shape in cross-section, the two branches diverging from their juncture with the single rectangular upper end of the lower section C. The lower section C is preferably hinged at its back or rear side by a hinge 17 of any suitable sort to the lower end of the telescopic section B, so that the section C can be swung forwardly or rearwardly to the position necessary to locate the branches properly in the upper portion of the car. The spout can be supported

in the position to which it is adjusted by any suitable means, such, for instance, as a prop 18, adapted to engage a cross-bar 19 or other projection on the rear side of 5 the branched section of the spout and to rest at its lower end on a platform 20 or other suitable support. The branches *c c* of the spout in addition to curving forwardly and diverging or curving laterally 10 away from each other, are also twisted so that the wall or side 21 of each branch, which is the back or rear side thereof at the upper end of the branch, becomes the inner side or wall of the branch at the discharge end 15 thereof. These sides or walls 21 at the discharge ends of the branches occupy a nearly upright position. The grain in flowing down through the chute and spout slides in a comparatively shallow stream or layer 20 on the inclined back or rear wall of the chute and the corresponding walls 21 of the spout, and, owing to the twist of the branches of the spout, the stream of grain continues to slide on these same walls 21 of the branches 25 of the spout and passes through the discharge end of each spout against the inner side thereof, as indicated in Fig. 8. Thus the descending stream of grain, although its direction is changed twice, first outwardly 30 and then laterally, nevertheless slides in contact with the same unbroken surface or wall of the spout. Its direction is thus changed gradually and without breaking the continuity of its flow or impeding its momentum, 35 and the grain is discharged from the branches of the spout under a momentum sufficient to throw it to the extreme ends of even the longest cars now in use. The grain strikes the end walls of the car and 40 the top of the rising mass of grain in the car with sufficient force to pile the grain up into the car to the roof thereof even between the transverse rafters of the roof so that the car is completely filled to its roof 45 and to the extreme ends of the car. In a spout which is not twisted, as explained, the grain is thrown from one wall of the spout to another, and this so checks the momentum of the grain that its discharge velocity is not sufficient to carry it to the 50 ends of the car or to cause the grain to pile up to the car roof.

Spouts of this kind are usually provided with a deflector or dividing device which is 55 adjustable to control the discharge of the grain through the branches of the spout in such manner as may be necessary to equalize or control the loading of opposite ends of the car, or to permit one-half only of the 60 car to be loaded, or one-half to be loaded with one grain and the other half with another grain. In the means shown in the drawings for this purpose, 22 indicates a stream deflecting or dividing device which 65 is pivoted in the spout above the point

where the two branches *c c* of the spout join and is adapted to be placed upright to direct the descending stream of grain equally into both branches of the spout, or to be set in a more or less inclined position for partially 70 or wholly shutting off one branch of the spout, and thereby causing a greater proportion or all of the grain to discharge through the other branch. This deflector or divider preferably consists of a plate bent into inverted V-form, or two plates or sides 23 secured together at an angle and arranged with the lower ends of the plates or sides straddling a cross rod 24 extending through the telescopic section B of the spout above 80 the juncture of the inner walls of the spout branches *c c*. The lower ends of the sides 23 are connected by a strip 25 by which the deflector rests on and is adapted to swing on the cross-rod 24. As the sides 23 of the 85 deflector form a sharp angle at their upper ends and straddle the cross rod and upper ends of the inner walls of the spout branches, the deflector does not offer an objectionable obstruction to the flow of the grain. A rod 90 26 secured to the deflector between its two plates or sides 23 extends out through an arc-shaped slot 27 in the front wall of the spout section B and passes through a slot 28 in an operating lever 29 which is suitably 95 pivoted at 30 to the section B of the spout. The deflector can be swung to any desired position by means of this lever and retained in such position by fastening the lever, as, for instance by tightening a nut 31 screwed 100 on the outer end of the rod 26, thereby clamping the lever between the nut and a sleeve 32 on the rod 26 between the lever and the spout section B.

The described construction enables the 105 deflector to be easily adjusted and held stationarily and rigidly at any desired angle, notwithstanding the great strain on the deflector incident to the impact of the grain against the same. Any other suitable form 110 of deflector may, however, be used.

While the spout is preferably provided, as explained, with two branches constructed as described for directing the grain simultaneously toward opposite ends of a car, a 115 spout having a single discharge end, constructed as described could be used advantageously and comes within the spirit of this invention.

The spout constructed as described is easy 120 to place in and adjust to the required position in a car, and it can be positioned just inside of the door opening near the side of the car or so as to project a considerable distance into the car, say, approximately two feet, without changing the position of the ends of the horn relative to the ends of the car. The ends of the horn discharge always directly toward the ends of the car instead of at an angle across the car. 130

The wear on the walls of the spout, or the liners, which are ordinarily used in the spouts, and the pressure on the prop or support 18 are much less than in former constructions, owing to the free, unimpeded delivery of the grain from the spout. Since the branched lower section of the spout is unbroken, or in one piece from end to end, instead of being composed of two or more 10 separate sections as heretofore, and the grain moves freely out of the spout without interruption or checking, the spout produces much less dust in operation than others, and is therefore not so bothersome to the man 15 who is required to stand on the platform to adjust or manipulate the spout when loading a car.

I claim as my invention:

1. A loading spout of the character described having a discharge portion which has bottom and side walls disposed at an angle to each other and curves downwardly, forwardly and laterally and is also twisted lengthwise so that the wall forming the 20 bottom of said discharge portion at the upper end thereof becomes the outer side wall at the discharge end thereof.
2. A loading spout of the character described having a discharge portion of substantially rectangular cross-section which curves forwardly and laterally and is also twisted so that opposite ends of the same 25 wall thereof are disposed respectively in substantially horizontal and vertical planes.
3. A loading spout of the character described comprising an upper section which inclines downwardly and forwardly so that the material descends in contact with the rear wall thereof, and a lower section which 35 is angularly adjustable relatively to said upper section and has a discharge portion

which has bottom and side walls disposed at an angle to each other and curves downwardly, forwardly and laterally and is also twisted lengthwise so that the wall forming 45 the bottom of said discharge portion at the upper end thereof becomes the outer side wall at the discharge end thereof.

4. In a loading spout of the character described, the combination of an upper section 50 having a downwardly and forwardly sloping rear wall, and a lower section having a downwardly, forwardly and laterally sloping wall constituting a continuation of said rear wall, said lower section being so twisted 55 lengthwise that the opposite ends of its said wall are disposed in planes at an angle to each other with the lower end thereof occupying a substantially upright plane, and said rear wall and said continuation 60 thereof together forming a continuous surface in contact with which the material slides through the spout.

5. A loading spout of the character described having a portion of polygonal cross- 65 sectional shape which curves downwardly and also laterally and is twisted so that the bottom of said downwardly curved portion and the outer side of the laterally curved portion constitute successive portions of the 70 same wall, whereby the material passing through the spout is caused by gravity and centrifugal force to slide on the same unbroken surface in turning said different curves and leaves the spout in contact with 75 said outer side wall thereof.

Witness my hand, this 29th day of September, 1917.

EDMUND M. HULL.
